UNITED STATES PATENT OFFICE.

CHARLES R. FORD, OF PADUCAH, KENTUCKY.

TUMBLER AND BOTTLE WASHER.

1,218,936.

Specification of Letters Patent.

Patented Mar. 13, 1917.

Application filed November 13, 1915. Serial No. 61,380.

To all whom it may concern:

Be it known that I, CHARLES R. FORD, a citizen of the United States, residing at Paducah, in the county of McCracken and State of Kentucky, have invented certain new and useful Improvements in Tumbler and Bottle Washers, of which the following is a specification.

This invention relates to improvements in devices for washing tumblers, bottles, and like devices, and has for one of its objects to simplify and improve the construction and increase the efficiency and utility of devices of this character.

15 Another object of the invention is to construct a device of this character adapted to be attached to the ordinary spigot in a sink, and operative by the force of the water flowing from the spigot.

Another object of the invention is to provide a device of this character which operates simultaneously to wash the glass or bottle both inside and outside, and likewise to brush the interior of the vessel.

Another object of the invention is to provide a device whereby the weight of the vessel to be cleansed is utilized to open a controlling valve and permit the cleansing liquid to flow when the vessel is inserted in the device.

Another object of the invention is to produce a device wherein provision is made for retarding the cleansing liquid within the vessel to increase the efficiency of the action.

With these and other objects in view, the invention consists in certain novel features of construction as hereinafter shown and described, and then specifically pointed out in the claim; and in the drawings illustrative of the preferred embodiment of the invention—

Figure 1 is a vertical sectional elevation of the improved device;

Fig. 2 is a transverse section on the line 2—2 of Fig. 1 detached from the supply spigot;

Fig. 3 is a transverse sectional view on the line 3—3 of Fig. 1.

Corresponding and like parts are referred to in the following description and indicated in all the views of the drawings by the same reference characters.

The improved device may be readily adapted without material structural change for washing glasses, bottles, and the like of various sizes and forms, but for the purpose

of illustration is shown with an ordinary drinking glass arranged to be cleaned, but it will be understood that it is not desired to limit the invention to any specific form or size of vessel to be cleansed.

The improved device includes a receptacle or casing, represented as a whole at 10, preferably constructed of metal and provided with an encircling tubular rim 11 communicating with the interior of the casing by a plurality of relatively minute apertures 12. Supported within the casing 10 is a supporting member or platform 13 upon which the lower end of the vessel to be cleansed rests, the latter being represented conventionally at 14. The upper face of the platform is flat or uniform in outline throughout, so that the rim of the vessel which is to be cleansed closely engages thereon as shown. A water driven motor casing 15 depends from the platform 13 and is supported from the bottom 16 of the casing by a plurality of standards or like devices 17. A tubular shaft 18 extends through the platform 13 and the casing 15 and is suitably packed, as represented at 19—20 to prevent water escaping around the shaft. A motor wheel 21 is connected to the shaft 18 within the casing 15, as shown. The supply pipe 22 for the motor is represented conventionally at 22 and leads through a suitable packing 23 in one side of the casing 10 and is turned upwardly and terminates in a controlling valve, represented conventionally at 24. A branch pipe 25 leads upwardly from the main supply pipe 22 into the tubular rim 11 of the casing, while another branch 26 leads downwardly from the main pipe 22 and thence into the casing 10 and is turned upwardly and terminates in a reduced nozzle 27 in the interior of the tubular shaft 18. A suitable packing 28 surrounds the supply pipe 26 where the latter passes through the side of the casing to prevent leakage. A waste pipe 29 leads from the bottom of the casing 10.

At one point in the platform 13 a socket is formed to receive the trip plate 31, the latter conforming to and completely filling the socket when the plate is in its withdrawn position, as shown in Figs. 1 and 2.

The trip plate is connected by a rod 30 to an arm 32 mounted to rotate with a shaft 34, the latter supported by a suitable bracket 35 and extending through a side of the casing 10 and suitably packed, as represented at 36.

Pivoted at 37 to a bracket 38 extending from the casing of the valve 24 is a lever arm 39 which engages the outer end of the stem 40 of the valve. At its outer end the 5 shaft 34 is provided with an arm 41, while the shaft 37 is provided with a similar arm 42, the two arms 41-42 being connected by a rod 43, for an object to be hereafter explained.

- 10 A conventional spigot 44 is shown and connected to the valve 24 by a reducing collar 45 of the usual construction. By this means the pressure of the water flowing through the spigot 44 will operate to normally 15 maintain the valve 24 closed and through the coaction of the various arms and rods the pin 30 with its trip plate 31 is maintained normally in its upper position, as indicated by dotted lines in Fig. 1. Thus 20 when no vessel is located within the casing 10 the water supply is shut off, but when a vessel, for instance the drinking glass 14, is deposited upon the platform 13 the weight of the glass will depress the trip plate 31 25 and thus force the opening of the valve and permit the water to flow.

The upper end of the tubular shaft 18 is provided with a plurality of lateral jets 46, and engaging over the tubular shaft is a 30 brush device including a tubular stock or head, represented as a whole at 47, and preferably constructed of open twisted wire work, the wire work being utilized to support the bristles of the brush, the latter being 35 represented conventionally at 48. The tubular stock 47 is considerably larger than the tubular shaft 18 so that a space is left between the shaft and the brush head for the free passage of the cleansing liquid. The 40 brush head 47 is preferably held in position by friction only, as represented at 49, and may thus be readily removed when desired. The flowing water causes the rotation of the motor wheel 21 and the shaft 18 and thus 45 rotates the brush against the interior of the vessel, and at the same time forces the water through the various jets simultaneously through the brush and against the interior of the vessel and likewise over the exterior 50 of the vessel, the waste water escaping through the member 29.

As before stated the upper face of the trip plate 31, when depressed, is flush with

the upper face of the platform 13, and thus forms a continuation of the same, and when 55 the vessel 14 is disposed by its rim upon the platform and the depressed trip plate, the flow of the water is retarded and held for a greater length of time within the vessel. The efficiency of the cleansing action is 60 thus materially increased, as will be obvious.

The improved device is readily adapted without material structural change to cleansing and washing vessels of various sizes and forms, and thoroughly cleans them both externally and internally. 65

All of the parts are of metal and may be galvanized or otherwise coated to prevent corrosion. The enlargement 31 of the trip rod 30 may be of any length to adapt the 70 device to tumblers, bottles, or other vessels of varying sizes.

Having thus described the invention, what is claimed as new is:—

A washing apparatus comprising a main 75 casing having a tubular rim around its upper end and provided with perforations through its wall communicating with the interior of said rim, a platform secured rigidly within said casing concentric therewith 80 and in spaced relation to the bottom and side walls thereof, said platform being adapted to support the article to be washed and having a socket in its upper side, a motor casing secured concentrically on the 85 under side of the platform, a tubular shaft extending through and journaled in said casing and platform and rising above the platform, a motor wheel secured to said shaft within said casing, a water supply pipe 90 leading to said motor casing, a branch leading from said water supply pipe to the hollow tubular rim of the main casing, a second branch leading from the water supply pipe through the main casing and terminating 95 within said hollow shaft, a brush secured on and around the upper end of the hollow shaft, a controlling valve mounted within the supply pipe, a trip plate arranged to fit within the socket in the platform and be depressed by the article to be washed, and operative connections between said trip plate and the controlling valve. 100

In testimony whereof, I affix my signature.

CHARLES R. FORD. [L. S.]
